UNITED STATES PATENT OFFICE.

JOHN W. SMITH, OF COLUMBIA, FLORIDA.

CAR-TRUCK.

SPECIFICATION forming part of Letters Patent No. 624,556, dated May 9, 1899.

Application filed March 1, 1899. Serial No. 707,265. (No model.)

To all whom it may concern:

Be it known that I, JOHN W. SMITH, a citizen of the United States, residing at Columbia, in the county of Columbia and State of Florida, have invented a new and useful Car-Truck, of which the following is a specification.

This invention relates to car-trucks; and the object of the invention is to provide a light and strong device of this character and which can be manufactured at a low cost and from standard and not special or pressed metal work.

With these ends in view the invention consists in the novel combination of elements and in the construction and arrangement of parts, which will be hereinafter fully described and claimed.

To enable others to understand the invention, I have illustrated the preferred embodiment thereof in the accompanying drawings, forming a part of this specification, and in which—

Figure 1 is a plan view of a portion of a car-truck constructed in accordance with the invention. Fig. 2 is a side elevation of the same. Fig. 3 is a cross-sectional elevation, the section being taken on the line 3 3 of Fig. 1 and looking in the direction of the arrow. Fig. 4 is a sectional elevation, the section being taken on the line 4 4 of Fig. 1 and looking in the direction of the arrow.

Like characters denote like and corresponding parts in each of the several figures of the drawings.

In the drawings I have deemed it necessary to simply show one-half of the truck constituting the invention, and said truck includes in its construction a side frame A, having at its opposite ends pedestal-spaces 2, of box-like formation, in which the usual axle-boxes are disposed, and the pedestal-frames, hereinafter more particularly described, entirely surround said journal-boxes (not shown) and are braced in such a manner as to produce a thoroughly staple structure capable of withstanding the severe strains to which apparatus of the present character are ordinarily subjected.

The side frame A includes in its construction a longitudinal channel beam or iron 3, constituting the main member thereof and

bent downwardly at its opposite ends, as at 4 and 5, at right angles to the main body thereof to form portions of the pedestal-frames. 55 In connection with this main channel beam or iron I provide the substantially inverted-U-shaped braces 6 and 7, respectively, of approximately flat steel throughout their length, the outer legs or branches of which are riveted at superposed points, as at 8, to the downwardly-bent extensions 4 and 5 of the channel-beam, and the cross or transverse portions of these braces are riveted at different points, as at 9, to the under side of the web of said 65 channel or beam at points adjacent to the opposite end of the latter.

The rivets 9, which connect the U-shaped braces and main channel-iron, also extend through the longitudinal flat plate 10, which 70 extends from one pedestal-frame to the other, as will be obvious, and which tends to further strengthen the structure, and this plate has an inward extension 12, against which and substantially at its middle the outer end 75 of the transom-plate 13 fits, said plate being secured in place by a series of rivets, as 14, in alignment with each other and passing through the two parts.

The pedestal-frames are further strengthened by a brace 15, of channel-iron, which is located above the lower ends of the interior braces 6 and 7 and which is bent downwardly at its opposite ends, as at 16 and 17, respectively, and at right angles to the main body 85 thereof. These downwardly-bent portions fit against the inner legs of the U-shaped braces 6 and 7, the parts being secured together by rivets, as 18, passing through the web of the brace or channel iron 15. A flat plate is 90 shown at 19, this being complementary to and in parallelism with the upper plate 10, and said plate 19 fits against the upper face of the web of the cross-brace 15, a series of rivets, as 20, passing through the two parts, and the 95 ends of this plate sustain the T-shaped coupling members 21 and 22, which are secured by rivets, as 23, at different points in the height thereof to the inner legs or branches of the U-shaped braces 6 and 7. A series of rivets, 100 as 24, connect the flanges of these coupling members with the right-angularly-bent ends 25 and 26, respectively, of the channel-beams or cross-girders 28 and 29, the flanges of the

latter fitting against the inner faces of the upper and lower parallel plates 10 and 19, respectively, and being secured together by rivets, as 30. The plate 13 is secured along 5 its opposite edges to the upper flanges of the channel-beams 28 and 29 by rivets, as 31, and to the lower flanges of these beams a similar plate 32 is secured by rivets, as 34, which pass through the two parts, and these upper and 10 lower plates 13 and 32 overlap the plates 10 and 19.

It is apparent that instead of employing T-shaped coupling members other-shaped devices could be substituted therefor without 15 departing from the spirit of the invention, and it is likewise obvious that other devices than rivets might be employed to hold the parts in assembled relation.

A car-truck constructed as aforesaid is 20 strong and light and is capable of withstanding the strains and shocks generally present, and it can be manufactured from standard metal shapes, thereby obviating the necessity of constructing special beams and the like 25 for its formation.

Changes in the form, proportion, size, and the minor details of construction within the scope of the appended claims may be resorted to without departing from the spirit or sacrificing any of the advantages of this invention.

Having thus described the invention, what I claim is—

1. In a car-truck, the combination with a 35 main beam having right-angular downward extensions, of inverted-U-shaped braces the outer legs or branches of which are secured to said downward extensions, a longitudinal brace secured to the inner branches of said 40 U-shaped braces, coupling members connected with the inner branches of said U-shaped braces, cross-beams having right-angular extensions at their ends secured to said coupling members, upper and lower plates secured to said cross-beams, and a second pair 45 of plates disposed in the spaces between said first-mentioned plates and the cross-beams.

and overlapped by said first-mentioned plates, substantially as described.

2. In a car-truck, the combination with a 50 main beam having right-angular downward extensions at its opposite ends, of inverted-U-shaped braces the outer legs or branches of which are secured to said downward extensions, a longitudinal brace having right-angular downward-extending portions secured to the inner branches of said U-shaped braces, coupling members connected with the inner branches of said U-shaped braces, cross-beams having right-angular extensions at their ends 60 secured to said coupling member, upper and lower plates secured to said cross-beams, and a second pair of plates disposed between said first-mentioned plates and the cross-beam, and overlapped by said first-mentioned plates, 65 substantially as described.

3. In a car-truck, the combination with a main channel-beam having right-angular, downward extensions, of inverted-U-shaped braces the outer legs or branches of which are 70 secured to said downward extensions and the cross portions of which are secured to the main portion of said beam, a longitudinal channel-brace having downwardly-bent right-angular portions secured to the inner branches 75 of said U-shaped braces, cross channel-beams having angular extensions at their ends, T-shaped coupling members secured respectively to the inner ends of said cross-beams and to the inner branches of the U-shaped 80 braces, upper and lower flat plates secured to the flanges of said cross-beams, and a second pair of plates disposed between said first-mentioned plates and the cross-bars and overlapped by said first-mentioned plates, substantially as described.

In testimony that I claim the foregoing as my own I have hereto affixed my signature in the presence of two witnesses.

JOHN W. SMITH.
